UNITED STATES PATENT OFFICE.

BYRON COBURN, OF CARDWELL, VIRGINIA.

MACHINE FOR CONVERTING MOTION.

SPECIFICATION forming part of Letters Patent No. 443,132, dated December 28, 1890.

Application filed September 9, 1890. Serial No. 364,401. (No model.)

To all whom it may concern:

Be it known that I, BYRON COBURN, a citizen of the United States, residing at Cardwell, in the county of Goochland and State of Virginia, have invented a new and useful Machine for Converting and Transmitting Motion, of which the following is a specification.

This invention relates to machines for converting and transmitting motion; and it has for its object to construct a device of this class which shall be simple, durable, and efficient in operation, and whereby the reciprocation of the hand-levers with which the machine is provided may be converted into rotary motion, which may be used for driving small machinery.

With these ends in view the invention consists in the improved construction, arrangement, and combination of parts, which will be hereinafter fully described and particularly pointed out in the claims.

In the drawings hereto annexed, Figure 1 is a plan view of a machine embodying my improvements. Fig. 2 is a side elevation of the same. Fig. 3 is a vertical transverse sectional view.

Like numerals of reference indicate like parts in all the figures.

The frame of my improved machine is preferably rectangular in shape, and the upper longitudinal frame-beams 11 are provided with boxes or bearings for the transverse shafts 2 and 3, the former of which carries at its outer end a spur-wheel 4, meshing with a segment 5, which is mounted upon the outer end of the shaft 3, and to which is attached a handle or lever 6, by means of which it may be conveniently manipulated. The shaft 2 also carries a drum 7, having flanges 8, which extend partially around its circumference, and which serve to guide the rope or cord, chain, belt, or the like 9, which is wound upon and secured by means of staples or in any other convenient manner to the perimeter of the drum-pulley in such a manner as to positively prevent its slipping. The ends of the rope or equivalent 9 are passed over pulleys 10, which are journaled upon shafts 11 at the ends of the frame.

The outer side beams of the frame are provided with longitudinal brackets 11^a, consisting of circular rods 15, the outer ends of

which are journaled or mounted in boxes 12 upon the legs or uprights 13 at the ends of the frame, and the inner ends of which have elbows 14 extending through the frame-beams and are secured by means of nuts and washers. The longitudinal rods 15 serve as guides for the longitudinally-sliding boxes 16, which are provided at their upper and lower ends with sleeves or bearings 17 for the said rods. The boxes 16 are also provided with centrally-located sleeves or collars 18, which are connected by means of a longitudinal rod 19, which, in conjunction with the sliding boxes 16, forms a longitudinally-reciprocating frame, the ends of which are suitably connected with the ends of the rope or belt 9^a, passing around the drum or pulley 7. One of these sliding boxes 16 is provided with a laterally-extending bracket 20, to which is pivotally connected a pitman 21, the free end of which is connected with a crank 22, formed at one end of the shaft 23, journaled transversely in the frame and carrying a fly-wheel or balance-wheel 24. The shaft 23 may also carry an additional wheel or pulley 25, from which motion may be transmitted by means of a belt or band to the machinery which is to be driven.

From the foregoing description, taken in connection with the drawings hereto annexed, the construction and operation of my invention will be readily understood. The operator, by manipulating the lever or handle 6, may impart an oscillating motion to the wheel or drum 7 upon the shaft 2, and thus transmit a reciprocating motion to the longitudinally-removable frame composed, essentially, of the end pieces or head-blocks 16 and the connecting-rod 19. The said frame in its reciprocatory movement actuates the pitman 21, and thus transmits a rotary motion to the shaft carrying the balance-wheel 24, from which motion may be readily conveyed to the machinery which is to be driven. It is obvious that by using a fly-wheel of sufficient size and weight sufficient impetus may be gained to drive all kinds of moderately-light machinery in an easy and efficient manner.

Instead of a single operating-lever 6, having toothed segment 5, two such levers may be employed, being arranged on opposite sides of the spur-wheel 4, the additional lever and

toothed segment having been shown in dotted lines in the drawings. By this arrangement two men stationed on opposite sides may simultaneously operate the machine.

5 Having thus described my invention, what I claim is—

1. In a machine for converting and transmitting motion, the combination of a rectangular frame, the longitudinal guide-rods secured to the outer sides of the side beams of said frame, the longitudinally-reciprocating frame comprising the head-blocks mounted upon the said guide-rods and connected by a longitudinal connecting-rod, means for imparting a longitudinally-reciprocatory motion to the said frame, and a pitman connecting one end of said frame with a crank upon a shaft having a balance-wheel, substantially as set forth.
- 10 2. In a device for converting and transmitting motion, the combination of the frame, the longitudinal guide-rods secured to the sides of the same, the reciprocating frame composed of the head-blocks mounted upon said guide-rods and connected by a central longitudinal rod, a drum or wheel mounted upon a suitable shaft and having a belt or band passing over guide-pulleys and con-

nected with the ends of the reciprocating frame, a lever having a segmental rack meshing with a spur-wheel upon the central oscillating shaft, and a pitman connecting one end of the longitudinally-reciprocating frame with a crank upon the end of a shaft carrying a fly-wheel, substantially as and for the purpose set forth.

3. In a machine of the class described, the combination of the frame having the longitudinal guide-rods, the head-blocks mounted to reciprocate upon the said guide-rods and connected by a central longitudinal rod, means for imparting a reciprocating motion to the frame thus formed, a bracket extending laterally from one of the reciprocating head-blocks, and a pitman connecting said bracket with a crank upon a transverse shaft carrying a fly-wheel, substantially as herein set forth.

In testimony that I claim the foregoing as my own I have hereto affixed my signature in presence of two witnesses.

BYRON COBURN.
